UNITED STATES PATENT OFFICE.

PHILIP T. HANDIGES, OF DETROIT, MICHIGAN, ASSIGNOR TO THE MICHIGAN MALLEABLE IRON COMPANY, OF DELRAY, MICHIGAN.

MACHINE FOR MOLDING CAR-AXLE BOXES.

SPECIFICATION forming part of Letters Patent No. 681,785, dated September 3, 1901.

Application filed April 13, 1901. Serial No. 55,614. (No model.)

To all whom it may concern:

Be it known that I, PHILIP T. HANDIGES, a citizen of the United States, residing at Detroit, county of Wayne, State of Michigan, 5 have invented a certain new and useful Improvement in Machines for Molding Car-Axle Boxes; and I declare the following to be a full, clear, and exact description of the invention, such as will enable others skilled in 10 the art to which it appertains to make and use the same, reference being had to the accompanying drawings, which form a part of this specification.

My present invention is designed more particularly to provide a novel machine for molding car-axle boxes, although it may be employed for other uses; but in the accompanying drawings and in the following description I have described and illustrated the same 20 as especially adapted for molding car-axle boxes; but I would have it definitely understood that I do not limit myself to molding any particular article of manufacture.

My invention consists of the structure, combination, and arrangement of devices herein-after described and claimed, and illustrated in the accompanying drawings, in which—

Figure 1 is a view in perspective illustrating the body or inclosing case. Fig. 2 is a 30 vertical cross-section through said box on the line 2 2, Fig. 4, and through a car-axle-box pattern and the flask, showing also portions of the interior construction within the body. In this view the pattern is shown in elevated 35 position. Fig. 3 is a similar view in vertical cross-section through the body and flask, the pattern being shown withdrawn into the body or case of the machine. Fig. 4 is a view in longitudinal section showing parts in elevation. Fig. 5 is a plan view of the body.

Among the objects of my invention is to provide a low machine to facilitate the operation of the same; also, to provide a portable machine.

45 In carrying out my invention the supporting-body or inclosing case of the machine is indicated at *a*. Supported therewithin are fixed standards *b* *b*. These standards are supported in any suitable manner, as upon 50 bases *c*. Upon each of said standards is located a supporting-sleeve *d*, said sleeves to

be engaged with a pattern *e*, supported thereupon. I have shown two standards, each provided with a supporting-sleeve *d*, engaged with the pattern; but I do not limit myself 55 to any definite number of standards, as one or more may be employed within the scope of my invention. The sleeves *d* may be engaged with the patterns in any suitable way, as by bolts *f*. The shaft *g* is shown provided with 60 an operating handle or lever *h*, said shaft being connected with a system of levers or "lazy-tongs" (indicated at *i*) to simultaneously operate said series of tongs if plural tongs are used. To this end the shaft may 65 be provided with crank-arms *j*, connected with said lazy-tongs. The lazy-tongs are connected at their upper ends with their respective sleeves *d* and at their lower ends may be engaged with the corresponding bases *c*. A 70 flask is indicated at *k*, into which the pattern is elevated and from which it is withdrawn by means of the lazy-tongs engaged with the shaft *g*. The body *a* is also provided with a top or cover *l* and also with trucks or wheels 75 *m*, whereupon the machine may readily be transported from one place to another. The base of the pattern is provided with an orifice, as at *n*, through which the corresponding standard *b* may enter the pattern when 80 the pattern is depressed or withdrawn into the body or inclosing case *a* and out of the flask. A lateral expansion of the pattern is indicated at *r*. The lazy-tongs are located beneath the patterns and when the pattern 85 is depressed are folded compactly therebelow. The crank-shaft is located to one side of the body and toward the base thereof, the crank-arms projecting underneath the pattern. 90

It will be obvious that I take advantage of the space in the pattern to permit the sliding of the pattern down over the standards, so that I am thus enabled to get a low machine. One great trouble with machines of this class 95 heretofore devised is their inconvenient height; but by utilizing the space within the pattern thus and by the folding movement of the lazy-tongs I am enabled to construct my machine in very close compass. The lazy- 100 tongs obviously will fold up compactly, so that I need to have the body of the machine

only of sufficient height to receive the folded lazy-tongs, together with the height of the pattern when slid down over the standards. By withdrawing the pattern into the box and 5 over the standards and by employing the lazy-tongs I get a machine easily worked in packing the sand in the flask about the pattern.

In operation the machine is placed at one end of a long row of molding-sand prepared 10 for molding, and as the molds are made they are placed before the machine and the machine drawn back to the place that was occupied by the sand used up in making the molds, thereby making it unnecessary to 15 carry the sand to the machine or to carry the molds away from the machine. If the machine were stationary, it would be obviously necessary to carry the sand to the machine; but by my construction I am enabled to roll 20 the machine along to follow up the said row as the sand is worked up into molds. Moreover, by the mechanism which I have employed a very short stroke of the lever or handle *h* will actuate the pattern either to 25 lift it up into the flask or to withdraw it into the body or case of the machine. To lock the pattern in its position within the flask, any suitable means may be employed—as, for instance, a couple of stops, (indicated at 30 *q q.*) The working parts of the machine are contained inside the supporting body or case.

What I claim as my invention is—

1. In a molding-machine, the combination 35 with a movable supporting-body, of a fixed standard carried by said body, a pattern reciprocatory upon said standard, a crank-shaft provided with a crank-arm journaled in said

body toward the base thereof and at one side the longitudinal center of the body, and lazy-tongs connected with said crank-arm and with said pattern to raise and lower the pattern, said lazy-tongs when the pattern is in depressed position folded beneath said pattern. 40

2. In a molding-machine, the combination with a supporting-body, of a stationary standard carried by said body, a supporting-sleeve reciprocatory upon said standard, a pattern engaged with the sleeve also reciprocatory 45 upon said standard, a shaft provided with a crank-arm journaled in said body toward the base thereof and at one side the longitudinal center of the body, and lazy-tongs located below said pattern connected with said crank-arm and with said sleeve to raise and lower the pattern, said crank-arm extending underneath the pattern, and the lazy-tongs when the pattern is in depressed position folded underneath said pattern. 50

3. In a molding-machine, the combination with a supporting-body, of plural standards carried by said body, a pattern reciprocatory upon said standards, plural lazy-tongs connected with said pattern, and a crank-shaft 55 journaled in said body connected with said lazy-tongs, said lazy-tongs when the pattern is in depressed position folded underneath said pattern.

In testimony whereof I sign this specification in the presence of two witnesses. 60

PHILIP T. HUNDIGES.
